(57) **CLAIM**

We claim the ornamental design for a throat of a racquet, as shown and described.

DESCRIPTION

FIG. 1 is a front, side perspective view of a throat of a racquet; FIG. 2 is an enlarged front, side perspective view of the throat of the racquet of FIG. 1;

FIG. 3 is a front view of the throat of the racquet of FIG. 1; FIG. 4 is a side view of the throat of the racquet of FIG. 1; FIG. 5 is a side view from a longitudinal axis of the throat taken along line 5-5 of FIG. 3.

FIG. 6 is a top view of the throat of the racquet taken along line 6°-0°-6° of FIG. 3; and,

FIG. 7 is a bottom view of the throat of the racquet taken along line 7°-0°-7° of FIG. 3.

The ornamental design that is claimed is shown in solid lines in the drawings. The broken (dashed) lines shown in FIGS. 1 through 5 and 7 are included for the purpose of illustrating environmental elements only and form no part of the claimed design.
